DESIGN FOR A GEM MOUNTING

Byard F. Brogan, Philadelphia, Pa.

Application May 15, 1935, Serial No. 56,837

Term of patent 3½ years

To all whom it may concern:

Be it known that I, Byard F. Brogan, a citizen of the United States, residing at Philadelphia, in the county of Philadelphia and State of Pennsylvania, have invented a new, original, and ornamental Design for a Gem Mounting, of which the following is a specification, reference being had to the accompanying drawing, forming a part thereof.

Fig. 1 is a side view of the gem mounting, showing my design.

Fig. 2 is an end view of the mounting, and Fig. 3 is a top plan view of same.

I claim:

The ornamental design for a gem mounting, as shown.

In witness whereof, I have hereunto subscribed my name.

BYARD F. BROGAN.
